Patented Nov. 20, 1917.

Ernst B. Kilian,
Inventor

By *Georg Kimmel.*
Attorney

UNITED STATES PATENT OFFICE.

ERNST B. KILIAN, OF HIGHLAND FALLS, NEW YORK.

ILLUMINATED SIGN.

1,247,403.

Specification of Letters Patent. Patented Nov. 20, 1917.

Application filed March 24, 1916. Serial No. 66,456.

To all whom it may concern:

Be it known that I, ERNST B. KILIAN, a citizen of the United States, residing at Highland Falls, in the county of Orange and State of New York, have invented certain new and useful Improvements in Illuminated Signs, of which the following is a specification.

The present invention relates to signs and more particularly to illuminated signs, an object of my invention being to provide a lamp attachment for supporting a license tag or the like adjacent a light support for rendering more clear the indicating matter formed on the tag.

Another object of my invention is to provide a combined light source and sign adapted for use in daylight and arranged to be adjusted for use in darkness. My invention is particularly adapted for use as a license tag for motor vehicles and the like but I do not limit myself to this application to this use since it will also be found particularly adaptable for use in connection with locomotive head-lights for carrying the number of the locomotive and making the same clearly discernible at night.

Other objects and advantages to be derived from the use of my improved illuminated sign will appear from the following detail description and the claim, taken with an inspection of the accompanying drawing, in which—

Figure 1 is a perspective view of a sign embodying the improvements of my invention, the sign being shown as an automobile license sign,

Fig. 2 is a top plan view of the same, showing the sign in position for use in darkness, and

Fig. 3 is a vertical sectional view taken on the line 3—3 of Fig. 1, looking in the direction of the arrows.

Referring more particularly to the drawing, in which similar characters of reference designate like and corresponding parts throughout the various views, 1 designates the base or rear section of my improved sign, said base being formed preferably of sheet metal or the like and formed with an offset extension 2 supporting a light source of any suitable character, an electric automobile rear lamp 3 being shown. The lamp 3 is provided with a light projecting portion 5 which is arranged to project light longitudinally

of the base 1 for a purpose which will hereinafter appear. The lamp 3 is provided with the usual red bull's-eye 6. The base 1 is adapted to be secured in position on an automobile body by means of a bracket 7. The designating portion of my improved sign comprises a front section 8 formed of sheet metal and hinged as at 9 to the base 1. The designating letters and numerals of the license are struck from the section 8 as indicated at 10 and are preferably painted black or some color strikingly different from the white background of the base 1. The section 8 is held in angular relation to the base 1, at times, by means of a link 11 slotted as at 12 to receive a threaded stud 13 on which is arranged a wing nut 14, the opposite end of the link being pivotally and permanently riveted as at 15 to the section 8.

As shown in Fig. 1 the invention is in position for use in daylight wherein the black letters designated 10 are allowed to become prominent against the white background of the base 1, the section 8 being swung rearwardly in parallelism with the said base 1 and locked in such position by means of the wing nut 14. When used at night time or in darkness the lamp is, of course, lighted and the section 8 swung into angular relation with the base 1, as best shown in Fig. 2 and locked in such position by means of the wing nut 14. In this position it will be seen that the light rays from the lamp 3 are projected between the base 1 and the section 8 and the white background of the base 1 reflects the light rays through the interstices between the letters formed in the section 8.

From the above description taken in connection with the accompanying drawing, it is thought that a clear and comprehensive understanding of the construction, operation and advantages of my invention may be had, and while I have shown and described my invention as embodying a specific structure, I desire that it be understood that I may make such changes on said structure as do not depart from the scope of the invention as claimed.

What I claim as new and desire to secure by Letters-Patent is;—

In an illuminated sign, a light source, a base having a reflecting background rigidly connected to the back of the light source, a front section having designating means

thereon hingedly connected to the said base, a threaded stud member formed on the upper edge of said base section, a rivet member formed on the upper edge of the said front section, a link member slotted intermediate the longitudinal edges thereof and adapted to slidably engage the said stud

member, and a winged nut arranged on the said threaded stud to lock the said front and base sections at any desired angle. 10

In testimony whereof I affix my signature hereto.

ERNST B. KILIAN.
